UNITED STATES PATENT OFFICE.

FREDERICK W. WILCKEN, OF ST. PAUL, MINNESOTA, ASSIGNOR TO THE NORTHWESTERN BEDDING AND MANUFACTURING CO., OF ST. PAUL, MINNESOTA, A CORPORATION OF SOUTH DAKOTA.

SELVAGE FOR BED-SPRING FABRICS.

Application filed July 29, 1922. Serial No. 578,442.

My invention relates to a selvage for a bed spring fabric, the primary object of which is to provide a reinforced border, which is adapted to extend in a plane with 5 the strands of the fabric, to form a broad, flat bearing surface for the mattress at the edge of the spring.

A feature of the invention resides in means in the form of a flat, thin, ribbon like member which extends from end to end, along 10 the marginal edge of the spring. This ribbon like member is of sufficient width to form a broad, flat surface for supporting the mattress and is held on its ends by helical springs, similar to those which hold the 15 fabric taut in the frame. The invention also includes individual strands of wire or other suitable material which are positioned and extend along either side of the ribbon like member and which constitute a part of 20 the selvage for the spring fabric.

In the drawings forming part of this specification:

Fig. 1 is a plan view of a portion of my 25 spring, including the new form of a selvage for the same.

Fig. 2 is an enlarged detail of a portion of the spring end selvage.

Fig. 3 is an enlarged side view of a 30 portion of the spring.

Fig. 4 is a section on the line 4—4 of Fig. 5.

Fig. 5 is a section on the line 5—5 of Fig. 2.

In the drawing, the spring A is formed 35 of a series of loops 12 which are made up of individual pieces of wire. The loops 12 are formed by bending the wire centrally between its ends, to form the parallelly extending strands 13 and 14, while the free ends of the same are secured together by a suitable clip 15, so as to rigidly secure the ends together. The loops with the strands 13 and 14 are supported on their ends by 40 suitable helical springs 16 which hold the strands of the loops taut between the end members B of the bed spring frame, in the original manner.

The spring A is made up of a series of 45 these loops 12, with the strands 14 and 15 and the respective loops extending parallel to each other throughout the breadth of the spring A from the fabric of the same.

The strands 14 and 15 are connected to

gether by means of the cross links 17 which 55 are spaced apart at intervals to hold the strands 13 and 14 equally separated apart at the point of connection. The strands 13 and 14 of the adjacent loops 12 are connected by the links 18 which are positioned between 60 the links 17. In this manner the respective strands of each of the loops are connected alternatively together across the spring A to form a series of transversely extending supporting means at the various points across 65 the surface of the spring.

The strands 13 and 14 of the loops are 70 formed of wire which is wound or wrapped with a series of small wires to form a rope like finish which strengthens the strands 75 and provides sufficient roughness to the same so that the connecting links 17 and 18 remain in their respective positions, after being tightly clamped in place. This prevents the links from creeping longitudinally 80 on the strands and also adds materially to the appearance of the fabric made up of these loops 12.

The selvage G of the spring A is formed 85 of two individual strands of wrapped wire 19 and 20 such as are used in making up the loops 12 of the fabric A. These strands 19 and 20 are formed with eyelets 90 21 and 22 respectively and ends 23 which extend beyond the eyelets on either end of the strands. The strands 19 and 20 are held spaced apart and supported on their ends by helical coil springs 24. The ends 23 of the strands 19 and 20 extend into the coils of the springs 24 and form supporting 95 means to strengthen the eyelets 21 and 22. This form of construction is economical and cheap to manufacture, forming a durable construction, as it is impossible for the eyelets 21 and 22 to become enlarged due 100 to the ordinary strain in use, owing to the supporting ends 23. This construction also protects the bed clothing against engagement with the ends 23 which would be apt to tear the mattress or bedding and thus be impractical in connection with the use 105 of the fabric. It is highly desirable to make up the entire fabric with no unfinished edges and in my invention I am endeavoring to accomplish this in a neat practical way.

A flat ribbon like strip 25 is interposed between the strands 19 and 20 and is held

on its ends by helical springs 26 which are interposed between the springs 24 and in close proximity to the same. The strip 25 is held in flat relation with, and approximately in the same plane as the strands 19 and 20, by means of two adjacent links 27 one of which extends on one side of the strip 25 and the other on the other side. At the point of engagement of the links 27 with the strip 25, the strip is formed with a shoulder 28 which is engaged by the links 27. This shoulder is formed by clamping the strip and ribbon 25 in connection with the links 27 and prevent longitudinal movement of the same. The strip 25 forms a flat, broad supporting surface for the mattress which is strong and durable and makes a selvage for the fabric of the spring, which with the strands 19 and 20 form sufficient width to prevent easy bending or twisting of the selvage out of shape when the spring is in use. This spring is economical to manufacture and its neatness in design is very desirable for a spring of this nature.

25 The strands 19 and 20 form guards for either side of the strip 25. This is essential to protect the mattress and bed clothing from the edge of the strip 25. The connecting links 27 hold the strip 25 to the guard strands 19 and 20 so that the same remain approximately in a single plane. In this manner the strip 25 cannot twist so as to project its longitudinal edges above the guard strands and thus forms a substantial 30 reinforced selvage for the spring.

35

In accordance with the patent statutes, I have described the principles of operation of my invention and have illustrated a part from which I now believe the best embodiment thereof, but I desire to have it understood that this is only illustrative and that the invention can be carried out by other means and applied to uses other than those set forth within the following scope. 40

I claim:

1. A selvage for bed springs, including a pair of wire strands extending in parallel relation to each other, a flat strand interposed between said wire strands, pairs of cross links connecting said wire strands, 50 said cross links being of similar formation and closely spaced and an offset formed in said flat strand adapted to lie between said pairs of connecting links, whereby said cables may be maintained in alinement. 55

2. A selvage for a bed spring fabric comprising a pair of spaced cables, a flat strip positioned between said spaced cables and pairs of connecting links secured to said cables lying adjacent one another, one of said links being positioned below and the other above said flat strip and recesses formed in said connecting links for holding said flat strip in proper relation to said cables and an offset formed in said flat strip between said connecting links, whereby both links are maintained substantially in the plane of the fabric. 60 65

FREDERICK W. WILCKEN.
